UNITED STATES PATENT OFFICE.

JOHN C. JUTHE, OF ALLSTON, MASSACHUSETTS.

DESIGN FOR A WHEELED TOY.

60,956.

Specification for Design.

Patented May 16, 1922.

Application filed May 15, 1919. Serial No. 297,404. Term of patent 3½ years.

To all whom it may concern:

Be it known that I, JOHN C. JUTHE, a citizen of the United States, residing at Allston, in the county of Suffolk and State of Massachusetts, have invented a new, original, and ornamental Design for a Wheeled Toy, of which the following is a specification, reference being had to the accompanying drawing, forming part thereof.

Fig. 1 is a view in side elevation of the toy showing my new design.

Fig. 2 is a top plan view thereof.

The base 1 is the shape of a canoe, and is supported by the wheels 2. The arms 3 of the figure of an Indian seated in the canoe are shown at a certain angle, but the particular angular position of the arms forms no part of the design because these arms revolve about the axis 4.

I claim:

The ornamental design for a wheeled toy, as shown and described.

JOHN C. JUTHE.
